US00D700707S

(12) **United States Design Patent**
Baumgarten

(10) **Patent No.:** **US D700,707 S**
(45) **Date of Patent:** **** Mar. 4, 2014**

(54) **REUSABLE/ADJUSTABLE COMPRESS HOLDER**

(76) Inventor: **Victoria L. Baumgarten**, Loganville, WI (US)

(**) Term: **14 Years**

(21) Appl. No.: **29/399,771**

(22) Filed: **Aug. 18, 2011**

(51) **LOC (10) Cl.** **24-04**

(52) **U.S. Cl.**

USPC **D24/189**

(58) **Field of Classification Search**

USPC D24/189; 602/41-56, 57, 67, 58, 59

(57) **CLAIM**

The ornamental design for a reusable/adjustable compress holder, as shown and described.

DESCRIPTION

FIG. 1 is a perspective front view of the reusable/adjustable compress holder in accordance with the present Invention; FIG. 2 is a front view thereof; FIG. 3 is a rear view thereof; FIG. 4 is a side view thereof; FIG. 5 is a first end view thereof; FIG. 6 is an opposite end view thereof; FIG. 7 is a front perspective view of another embodiment of the reusable/adjustable compress holder wherein the strap elements are detached from one another; FIG. 8 is a front view thereof; FIG. 9 is a rear view thereof; FIG. 10 is a side view thereof; FIG. 11 is a first end view thereof; and, FIG. 12 is an opposite end view thereof. The broken lines depict portions of the reusable/adjustable compress holder that form no part of the claimed design.

1 Claim, 8 Drawing Sheets
